UNITED STATES PATENT OFFICE.

MAYLON LA QUAY, OF BATTLE CREEK, MICHIGAN.

LUBRICATOR FOR MULTISTAGE COMPRESSORS.

Application filed February 21, 1925. Serial No. 10,863.

To all whom it may concern:

Be it known that I, MAYLON LA QUAY, a citizen of the United States, residing at Battle Creek, county of Calhoun, State of Michigan, have invented certain new and useful Improvements in Lubricators for Multistage Compressors, of which the following is a specification.

This invention relates to improvements in 10 lubricators for multistage compressors.

This application is a continuation in part of my application for Letters Patent filed July 7, 1924, Serial No. 724,733.

My improved lubricator is especially designed by me for use with compressors of air brake apparatus and I have illustrated my improvements as embodied on such an apparatus. My improvements are, however, readily adapted for multistage compressors 20 designed for other uses.

The main objects of my invention are:

First, to provide an improved lubricator for compressors by means of which the lubricant is uniformly fed to the cylinders 25 in desired quantities.

Second, to provide an improved lubricator which is not likely to become inoperative or clogged in use.

Third, to provide an improved lubricator 30 which does not "flood" when idle.

Objects relating to details and economies of construction and operation will definitely appear from the detailed description to follow.

35 I accomplish the objects of my invention by the devices and means described in the following specification. The invention is clearly defined and pointed out in the claims.

A structure which is a preferred embodiment of my invention is clearly illustrated in 40 the accompanying drawing, forming a part of this application, in which:

Fig. I is a side elevation of a compressor embodying the features of my invention, the 45 parts being shown mainly in conventional form.

Fig. II is a vertical section on a line corresponding to line 2—2 of Figs. I, III and IV.

50 Fig. III is a plan view of the lubricant receptacle with the cap removed.

Fig. IV is a detail section on a line corresponding to line 4—4 of Fig. II.

In the drawing similar reference characters refer to similar parts throughout the 55 several views, and the sectional views are

taken looking in the direction of the little arrows at the ends of the section lines.

Referring to the drawing, 1, 1 represent the steam cylinders, 2 the high pressure 60 pump cylinder and 3 the low pressure pump cylinder. The details of the valves and connections for the cylinders are not illustrated as they form no part of my invention.

My improved lubricator is supported by a 65 bracket 4 adapted to be attached by one or more of the head screws 5 of one of the steam cylinders. The lubricant receptacle 6 is secured to this bracket by the screws 7. The lubricant chamber 8 of the receptacle 70 is provided with a closure plug 9 through which the receptacle is filled.

Formed in the walls of the receptacle are 75 passages 10 and 11, the passage 10 being connected to the low pressure cylinder by means of the pipe 12 which is, in effect, a part of the passage, and the passage 11 being connected to the high pressure cylinder by the pipe 13 which is in effect a part of the passage 11.

The passage 10 communicates with the chamber 8 through the restricted passage 14 and is provided with a check valve 15 seating towards the cylinder, that is, acting to prevent return to the cylinder through the 85 passage 10. The passage 11 communicates with the top of the lubricant chamber through the restricted connection 16 in the top of the receptacle and the coacting passage 17 in the cap or closure. The passage 90 16 opens to a segmental groove 18 in the top of the receptacle thereby adapting the structure to such variations as occur in starting the threads or variations in cutting the threads.

The passage 11 is provided with an upwardly seating valve 19 in advance of the restrictions, this upwardly seating valve preventing the air from the high pressure cylinder entering the lubricant chamber on the 100 work stroke.

In the embodiment illustrated the valve seat 19' is formed in a plug 20 threaded into the upper end of the passage 11, this plug having ports 19" communicating with the passage 16. The passage 14 has a branch 14' extending to the receptacle wall and adapted to be closed by the cap, the passage being open when the cap is removed so that the receptacle may be filled with the pump 110 running, if desired.

I also form in the wall of the receptacle a

cylinder 21 having an enlargement 22 in the low pressure end thereof.

The ends of the cylinder are open to the passages 10 and 11. The cylinder is provided with an inlet connection to the lubricant chamber which is, in the embodiment illustrated, a pipe 23 which extends upwardly into the receptacle and into the closure 19 which is chambered to receive the same. The pipe 23 is provided with inlet ports 24 adjacent the top of the receptacle.

The plunger 25 is provided with a head portion 26 coacting with the enlarged portion 22 of the cylinder. This head portion 15 has a port 27 therein disposed so that it is closed when the head portion of the plunger is at the inner end of the enlargement of the cylinder as shown in Fig. II.

The outstroke of the plunger is limited 20 by the adjustable stop 28 and by adjusting this stop the feed may be regulated to a considerable degree. This stop has a restricted opening 29 therein so that there is a restriction between the feed cylinder and the low 25 compression cylinder.

A restricting member 30 having a small opening 31 therein is disposed between the feed cylinder and the high pressure cylinder of the compressor.

30 With the parts thus arranged, on the up-stroke of the low pressure cylinder piston the plunger 25 is seated closing the port 27 and the air is forced past the check valve 15 of the passage 10 into the lubricant receptacle. On the up-stroke of the high pressure cylinder piston the air is kept from passing to the lubricant receptacle by the check valve 19.

The lubricant is heated to a considerable 40 temperature in practice and this, with the action of the air forced in as stated from the low pressure cylinder, atomizes the lubricant and forces it through the ports 24 to the plunger cylinder 21 and also a portion 45 of it is forced through the restricted passage 16 past the valve 19, which is then rising on the non-circular support as shown in Fig. IV, and through the restriction 31 to the high pressure cylinder, a certain quantity 50 of lubricant being also drawn on the down-stroke of the high pressure cylinder piston from the cylinder 21.

On the up-stroke of the high pressure cylinder the plunger 25 is forced toward the 55 right and lubricant forced by the air from the high pressure cylinder into the low pressure cylinder.

My improved lubricator is found highly efficient resulting in effective lubrication 60 without an excess of lubrication.

I have illustrated and described my improvements in a simple and practical embodiment and as especially designed for compressors used in brake systems. I have 65 not attempted to illustrate or show certain

embodiments or adaptations which I contemplate as I believe this disclosure will enable the application of my improvements as may be desired.

Having thus described my invention what 70 I claim as new and desire to secure by Letters Patent is:

1. The combination with a compressor comprising high and low pressure cylinders, of a lubricant receptacle with high and low 75 pressure cylinder passages opening to the top of the receptacle, the low pressure cylinder passage being provided with a return check valve and the high pressure cylinder passage being provided with an out-stroke 80 check valve, there being restrictions in the passages between said valves and the lubricant receptacle, a feed cylinder communicating at its ends to said passages, said feed cylinder being enlarged at the low pressure 85 end thereof, there being restrictions in said passages between said feed cylinder and said compressor cylinders, an inlet conduit for said feed cylinder opening to said lubricant receptacle at the top thereof, and a plunger 90 in said feed cylinder having a head coacting with the enlarged portion of the cylinder, said head having a port therethrough disposed so that it is closed when the head of the plunger is at the inner end of the enlarged portion of the cylinder.

2. The combination with a compressor comprising high and low pressure cylinders, of a lubricant receptacle with high and low 100 pressure cylinder passages, a feed cylinder communicating at its ends to said passages, said feed cylinder being enlarged at the low pressure end thereof, an inlet conduit for said feed cylinder opening to said lubricant receptacle at the top thereof, and a plunger 105 in said feed cylinder having a head coacting with the enlarged portion of the cylinder, said head having a port therethrough disposed so that it is closed when the head of the plunger is at the inner end of the enlarged portion of the cylinder.

3. The combination with a compressor comprising high and low pressure cylinders, of a lubricant receptacle with high and low 110 pressure cylinder passages opening to the top of the receptacle, the low pressure cylinder passage being provided with a return check valve, the high pressure cylinder passage being provided with an out-stroke 115 check valve, there being restrictions in the passages between said valves and the lubricant receptacle, a feed cylinder having an inlet connection to said receptacle and communicating at its ends to said passages, said feed cylinder being enlarged at the low pressure end thereof, there being restrictions in said passages between said feed cylinder and said compressor cylinders, and a plunger in said feed cylinder having a head coacting 120 with the enlarged portion of the cylinder.

4. The combination with a compressor comprising high and low pressure cylinders, of a lubricant receptacle with high and low pressure cylinder passages connected to said high and low pressure cylinders and opening to the top of said lubricant chamber, a feed cylinder having an inlet connection to said receptacle and communicating at its ends to said passages, said feed cylinder being enlarged at the low pressure end thereof, and a plunger in said feed cylinder having a head coacting with the enlarged portion of the cylinder, said head having a port therethrough disposed so that it is closed when the head of the plunger is at the inner end of the enlarged portion of the cylinder. 65
5. The combination with a compressor comprising high and low pressure cylinders, of a lubricant receptacle with high and low pressure cylinder passages connected to said high and low pressure cylinders and opening to the top of the lubricant chamber and also through the top wall thereof, a closure cap for said lubricant chamber adapted also to cover the outer ends of said passages, a feed cylinder having an inlet connection to said receptacle and communicating at its ends to said passages, said feed cylinder being enlarged at the low pressure end thereof, and a plunger in said cylinder having a head coacting with the enlarged portion of the cylinder. 70
6. A lubricator for multistage compressors comprising a lubricant receptacle with high and low pressure cylinder passages communicating with the top of said receptacle, the low pressure passage having a return check valve therein, a feed cylinder having a feed connection to said receptacle and opening at its ends to said passages and having an enlargement at the low pressure end thereof, a plunger having a head portion coacting with the enlarged portion of said cylinder, and having a port therethrough disposed so that it is closed when the head is at the inner end of said enlarged portion of said cylinder. 75
7. A lubricator for multistage compressors comprising a lubricant receptacle with high and low pressure cylinder passages communicating with the top of said receptacle, a feed cylinder having a feed connection to said receptacle and opening at its ends to said passages and having an enlargement at the low pressure end thereof, a plunger having a head portion coacting with the enlarged portion of said cylinder, and an adjustable stop at the head end of said plunger. 80
8. A lubricator for multistage compressors comprising a lubricant receptacle with high and low pressure cylinder passages communicating with the top of said receptacle, a feed cylinder having a feed connection to said receptacle and opening at its ends to said passages and having an enlargement at the low pressure end thereof, a plunger having a head portion coacting with the enlarged portion of said cylinder, and an adjustable stop for said plunger. 85
9. The combination with a compressor comprising high and low pressure cylinders, of a lubricant receptacle with high and low pressure cylinder passages connected to said high and low pressure cylinders and opening to the top of said lubricant receptacle, said low pressure passage having a return check valve, a feed cylinder having a feed connection to said receptacle and communicating at its ends to said passages, and a plunger in said cylinder. 90
10. A lubricator for multistage compressors comprising a lubricant receptacle with high and low pressure cylinder passages communicating with the top of said receptacle, the low pressure passage having a return check valve therein, a cylinder having an inlet opening to said receptacle and opening at its ends to said passages and having an enlargement at the low pressure passage end thereof, and a plunger having a head portion coacting with the enlarged portion of said cylinder and having a port therethrough disposed so that it is closed when the head is at the inner end of said enlarged portion of said cylinder. 95
11. A lubricator for multistage compressors comprising a lubricant receptacle with high and low pressure cylinder passages communicating with the top of said receptacle, a cylinder having an inlet opening to said receptacle and opening at its ends to said passages and having an enlargement at the low pressure passage end thereof, and a plunger having a head portion coacting with the enlarged portion of said cylinder and having a port therethrough disposed so that it is closed when the head is at the inner end of said enlarged portion of said cylinder. 100
12. A lubricator for multistage compressors comprising a lubricant receptacle with high and low pressure cylinder passages communicating with the top of said receptacle, the low pressure passage having a return check valve therein, a cylinder having an inlet connection to said receptacle, said cylinder being open at its ends to said passages and having an enlargement at the low pressure passage end thereof, and a plunger having a head portion coacting with the enlarged portion of said cylinder. 105
- In witness whereof I have hereunto set my hand.

MAYLON LA QUAY.
